UNITED STATES PATENT OFFICE.

NATHAN ELLIS, OF SYRACUSE, NEW YORK.

SANITARY SHAVING-BRUSH.

1,056,650.

Specification of Letters Patent. Patented Mar. 18, 1913.

Application filed April 16, 1912. Serial No. 691,105.

To all whom it may concern:

Be it known that I, NATHAN ELLIS, a citizen of the United States, residing at Syracuse, in the county of Onondaga and State of New York, have invented new and useful Improvements in Sanitary Shaving-Brushes, of which the following is a specification.

The general object of this invention is 10 the provision of a sanitary shaving brush having a handle in which there is provided a soap containing reservoir and means carried by said reservoir for forcing the soap therefrom and feeding it to the brush proper 15 whereby the operation of lathering the face is greatly facilitated.

In carrying out the objects of the invention generally stated above, it will be understood, of course, that the essential features 20 thereof are susceptible of changes in details and structural arrangements, one preferred and practical embodiment being shown in the accompanying drawing, wherein:—

Figure 1 is a side elevation of the brush 25 constructed in accordance with the invention. Fig. 2 is a vertical longitudinal sectional view thereof. Fig. 3 is a section on the line 3—3 of Fig. 2.

Referring more particularly to the accompanying drawing in which like reference characters designate similar parts, it will be seen that the invention comprises a handle 5 having a longitudinally extending opening 6 therein, said handle being provided 30 at its ends with the externally threaded extensions 7 and 8. An internally threaded ferrule 9 has a brush 10 secured thereto in the ordinary well known manner and said ferrule is adapted to be threaded upon the 35 extension 8 of the handle 5. Detachably secured to the extension 7 of the handle is an internally threaded cap 11 having a centrally located opening 12 for a purpose 40 which will be hereinafter more fully described.

Mounted in the longitudinal opening 6 of the handle 5 is a soap containing reservoir 13 having a removable cap 14 at its outer end and a nipple 15 at its inner end 45 which is adapted to project a distance into the brush and to which is secured a flexible tube 16 made of any suitable material such as rubber, said tube being provided adjacent its outer extremity with the oppositely disposed openings 17 through which the soap 50 is adapted to be fed to the brush in a man-

ner presently described. Mounted in a bearing 18 carried by the reservoir 13 adjacent the side wall thereof is a rotatable threaded shaft 19. The other end of the shaft 19 is 60 mounted in a suitable bearing 20 carrying a pinion 21 thereon, said bearing 20 projecting through the cap 14 of the reservoir.

The shaft 19 is adapted to be rotated in its bearings by means of a gear wheel 21 65 which meshes with the pinion 22 and which is mounted upon the extension 23 carried by a turning knob 24 which projects through the opening 12 formed in the cap 11, said extension 23 extending through the cap 14 70 and being adapted for loose engagement therewith so that the knob 24 can be freely rotated without rotating the said cap. The knob 24 is provided with an annular flange 25 which is slightly larger in diameter than 75 the opening 12 thereby preventing the withdrawal of said knob from engagement with the reservoir until the cap 11 is removed from engagement with the handle 5. A plate 26 having an internally threaded bearing 27 is adapted to engage the shaft 19 and upon rotation of said shaft, said plate will be caused to move back and forth within the reservoir. It will thus be seen that upon rotation of the knob 24 in one 80 direction, the shaft 19 will be rotated through the medium of the gear wheel 21 and pinion 22 thus causing the plate 26 to move outwardly and force the soap through the nipple 15 into the tube 16 and out 85 through the openings 17 therein to the brush. 90

From the foregoing description taken in connection with the drawing, it will be seen that the invention contemplates providing 95 an improved shaving brush which is simple in construction, durable and effective in operation.

It will also be obvious that the several parts can be readily removed after unscrewing the cap 11 from the handle 5 whereby the reservoir may be thoroughly cleansed and thus render the brush sanitary.

What is claimed is:—

1. A brush comprising a handle, a reservoir mounted in said handle and extending longitudinally thereof, a shaft rotatably mounted in said reservoir interiorly thereof, a gear wheel carried by said shaft, a rotatable knob connected to said reservoir and having means for engaging said gear wheel for rotating said shaft, and means carried

by said shaft for forcing soap from said reservoir.

2. A brush comprising a handle, a reservoir mounted in said handle, a shaft rotatably mounted in said reservoir adjacent the inner wall thereof, a bearing carried by the reservoir for receiving the inner end of said shaft, means rotatably mounted in one end of said reservoir and operatively con-

nected to said shaft for rotating the same, 10 and means carried by said shaft for forcing the soap from said reservoir.

In testimony whereof I affix my signature in presence of two witnesses.

NATHAN ELLIS.
